CHECK BOOK

William Roy Hotchkiss, St. Paul, Minn.

Application October 24, 1936, Serial No. 107,436

12 Claims. (Cl. 281—19)

The present invention relates to an improvement in pocket check books of a type particularly designed to accommodate a small number of checks in a compact folder. The invention also includes a particular construction of check book wherein the memorandum portion of the book may be folded flat with respect to the checks themselves, to facilitate the recording of a memorandum of the dates on which the checks were written, as well as a notation of the recipient of the check, the amount of the check, the balance of the account, and other desired information. It is also my invention to provide a cover for a book of checks which may be quickly and easily fastened in closed position without having the fastening device protrude outside the cover.

A great number of check books of various types have been designed in the past. One common type of check book is provided with a backing member or cover somewhat longer and slightly wider than a pad of checks. The pads of checks used therein usually comprise a stub portion of sufficient width to permit the recording of memoranda, to each stub of which is connected by a perforated line a blank check. An anchoring tongue is bound integrally to the stub portion of the pad of checks, which slidably engages in a pocket formed near one end of the backing member or cover the pad of checks, as well as the backing member or cover, is folded between the ends thereof. A closing flap at one end of the backing member or cover overlaps the opposite end of the backing member when in folded position, and is held in this position by a snap fastener or the like.

This type of check book is disadvantageous for a number of reasons. The construction makes a bulky cover. The length of the checks with the stubs attached make necessary a long container, even though the checks were folded centrally. The closing flap, extending over the outside of the container and fastened in place, made the container even thicker than without this flap, and made a bulky protrusion preventing it from sliding freely into a pocket or purse containing other articles.

My invention is designed to overcome the disadvantages of the folded type of check container, and to provide a check book of small dimensions which is compact and convenient to carry in the pocket or purse, and which is convenient to use. For this reason it is my purpose to provide pads of checks containing a comparatively small number of checks, and to support these checks in

such a manner that they are readily accessible for use and in a cover container that will slide easily in and out of a pocket or purse.

It is a purpose of my invention to provide a closure means for a folding check book of a type designed to obviate the over-lapping closure flap previously used. This closure comprises a hook means secured at one end of the foldable backing member or cover, which hooks into engagement with the bound end of the pad of checks held in a pocket in the backing member or cover in the usual manner; or into engagement with a pocket arranged for this purpose formed at the opposite end of the cover from the hook. This hook means is preferably spaced inwardly somewhat from the extreme edges of the backing member, and accordingly is out of contact with other articles held in the same pocket or purse.

These and other features and objects of my invention will be more clearly and fully set forth in the following specification and claims.

In the drawings forming a part of my specification:

Figure 1 is a side elevation view of my check book in folded position. 25

Figure 2 is a side elevation view of my check book in open position.

Figure 3 is a top plan view of my check container with checks in unfolded position.

Figure 4 is a longitudinal section through my check book, showing a portion of the same in perspective.

Figure 5 illustrates a pad of checks to be used in my check book, showing the construction before the memorandum portions have been affixed thereto.

Figure 6 is a perspective view of a fragmentary portion of the pad of checks shown in Figure 5, showing the memorandum portion in position with relation thereto, and ready for attachment. 40

Figure 7 is a longitudinal enlarged section through the one end of my check book in folded or closed position.

Figure 8 is a top plan view of a modified form of construction, showing my check book cover in open position.

Figure 9 is a cross-sectional view, enlarged, and taken on the line 9—9 of Figure 8.

Figure 10 is a perspective view of a reinforcing sheet used in one end of my check book cover in the modification shown in Figure 8.

Figure 11 is a perspective view of a reinforcing sheet used in the other end of my check book cover shown in Figure 8.

My check book A comprises a covering member 55

B and a filler C therefor. The covering member B is formed of a sheet of paper, fabric, leather, fibre or the like, and comprises a sheet 10 of rectangular shape and slightly larger than the pad of checks to be accommodated therein. The sheet 10 is reinforced by a pair of stiffening members 11 and 12, over the edges of which the marginal edge 13 of the sheet 10 are folded and adhered, providing a turned edge entirely about the periphery of the covering member. It will be noted that the stiffening members 11 and 12 extend throughout virtually the entire area of the sheet 10, with the exception of a strip 14 at the center of the sheet which is not reinforced, providing a more flexible central strip through which the covering member B may be folded.

A closing hook 15 is secured near one end of the covering member B. This closing hook comprises an anchoring plate 16, from which extends along one edge a curved hook shaped flange 18, terminating in a portion substantially parallel to, and spaced from, the anchoring plate 16. The anchoring plate 16 is formed, as may be seen, wider at the edge thereof opposite the closing hook flange 18, and the hook flange 18 is connected to the wider portion of the anchoring plate 16 by a narrower portion 19 of the anchoring plate. This construction forms a pair of shoulders 20 which firmly anchor the closing hook 15 to the cover in a manner which will be hereinafter more clearly described. If desired, an opening 21 may be formed through this plate 16, the purpose of which will also be later described in detail.

A pocket 22 is formed adjacent the end of the covering sheet 10 opposite the end thereof supporting the closing hook 15. This pocket is formed by a stiffening sheet 23 overlying the stiffening sheet or member 11. Throughout the length of this stiffening sheet 23, the marginal edges 13 of the covering sheet 10 enclose the edges of this sheet as well as the stiffening sheet 11, thus firmly securing the side edges of the stiffening sheet 23 to the covering sheet 10. An inner lining member 24 or fly sheet is glued over the inturned edges of the covering member 10, over the anchoring plate 16 of the fastening hook 15, and is turned over the free edge 25 of the pocket 22, as may be seen in Figures 4 and 7 of the drawings. The marginal edge 13 of the covering sheet 10 adjacent the open end 25 of the pocket 22 is sufficiently wide to conceal the stiffening sheet 11, the end 25 of the pocket 22 overlapping this marginal edge 13.

As may be seen in Figure 4 of the drawings, the stiffening means terminates at its inner end 26, as does the stiffening sheet 11, at a point spaced from the longitudinal center of the covering sheet 10 to provide the central flexible strip 14. This inner end 26 of the stiffening member 23 is held closed by the inner lining 24, which is secured directly to the inner surface of the covering sheet 10 over the area of the flexible strip 14.

The lining sheet 24 also extends over the anchoring plate portion 16 of the closing hook 15. As this closing hook is formed of relatively stiff material, such as metal, and anticipating that the liner 24 will not adhere to this closing hook as well as to the stiffening member 12 which the anchoring plate 16 overlies, the hook flange 18 is spaced by the narrower strip 19 to the wider portion of the anchoring plate 16. The liner 24 is accordingly adhered to the stiffening member 12 on either side of the narrower portion 19 of the closing hook 15, sealing the anchoring

plate from four sides. The shoulders 20 formed by the provision of the narrower portion 19 are locked by the adherence of the lining member 24 to the stiffening member 12.

In the form of construction at present in commercial use, the opening 21 through the anchoring plate 16 is eliminated. If a more secure anchor for the closing hook 15 is desired, however, the opening may be provided, so that the inner lining 24 may adhere to the stiffening member 12 through this opening, sealing the closing hook 15 even more securely in position.

The pad of checks 27 forms a part of the filler C. The pad 27 comprises a series of superimposed blank checks, each having a line of perforations 29 parallel to, and spaced a short distance from, one end thereof, to provide a binding margin 30 for each check 31. The superimposed checks 31 are attached together by staples 32 or other suitable means extending through the binding margins 30 on each check 31. An anchoring tongue 33 adapted to extend into the pocket 22 to hold the pad 27 in place is also attached by means of the staples 32 to the binding margins 30 of the checks. A strip of tape 34 extends over the binding margins 30 of the checks, and a portion of the anchoring tongue to cover the staples 32 and to more effectively bind these elements together.

The memorandum portion 35 of the filler C 30 comprises a series of sheets 36 centrally secured together by stitching 37 or the like, illustrated in Figures 6 and 7 of the drawings. In Figure 6 of the drawings the memorandum portion 35 is shown overlying the check pad 27, while a flexible tape 39, adhered to the bottom of the check pad, over the strip of tape 34, is ready for attachment with the upper surface of the memorandum portion 35. Figure 7 shows the tape 39 over, and attached to, the uppermost sheet 36 of the memorandum portion 35. The stitching 37 permits the various leaves 36 to be folded from the center, each sheet 36 forming two leaves of the memorandum portion 35. The indicia 40 on the sheets 36, upon which a record of the various checks is to be kept, is directly above the pad of checks 27 when written entries are to be made thereupon, thereby assuring the use of a flat and smooth surface for writing.

The cover D illustrated in Fig. 8 comprises a covering sheet 41, over which are positioned a pair of spaced reinforcing plates 42 and 43. A stiffening sheet overlies one reinforcing plate 42, to form a pocket 44 between the stiffening sheet 45 and the reinforcing plate 42. The marginal edges 46 of the sheet 41 are folded over the edges of the plates 42 and 43 along the sides and ends of the cover, to provide a turned edge. A lining sheet 47 overlies the reinforcing plate 47 and the stiffening sheet 45, and is adhered thereto. This lining sheet 47 overlaps the marginal edges 46 of the sheet 41, to conceal these edges. The end 49 of the lining sheet 47 is folded over the free edge of the stiffening sheet 45 to provide a turned edge for the pocket 44.

The reinforcing plates are formed of metal or of comparatively rigid material. At one end 50 of the plate 43, a pair of spaced slots 51 extend into the body of the plate 43. Between these slots 51 a hook 52 is formed by bending this portion of the material forming the reinforcing plate into hook shape. In this manner, the hook 52 is formed at a point spaced inwardly slightly from the extreme end 50 of the plate 43. By this construction the hook is made integral with the re-

inforcing means, eliminating a separate reinforcing means and simplifying the assembly of the cover D.

In the use of my check book, the filler C is attached to the covering member B by sliding the anchoring tongue 33 into the pocket 22. The backing member B, and the filler C therein, may then be folded between the ends thereof. As may be seen in Figure 4, an area on each side of the longitudinal center of the covering member B, comprising the strip 14, is not reinforced by any reinforcing stiffening member 11, 12, or 23, permitting the covering member to fold readily at this point. The memorandum portion 35, being in length less than one half the length of the check pad 27, need not be folded, and is enclosed within the folds of the check pad 27 when the book A is in folded position.

To hold the book A closed, it is only necessary to hook the closure hook 15 over the bound end of the filler C. As the filler C is attached to the end of the covering member B opposite to that bearing the hook 15, the book A will be held in closed position in this simple manner. If desired, the hook flange 18 of the closing hook 15 may engage into a pocket such as 22, to hold the end of the covering member supporting the hook 15 directly to the opposite end of the cover. In such a construction, some other means of providing support for the checks to the covering member is used. As has been noted, the hook 15 is recessed or spaced inwardly from the edge of the covering sheet 10, so that the hook 15 will not engage other articles which may be kept in the same pocket or purse, and so that this hook cannot engage or tear the fabric with which the check book A may come into contact.

Although I have illustrated a preferred embodiment of my invention, it will be readily understood that various changes coming within the spirit of my invention may suggest themselves to those skilled in the art, and hence I do not wish to be limited to the specific form shown or uses mentioned, except to the extent indicated in the appended claims, which are to be interpreted as broadly as the state of the art will permit.

I claim:

1. A pocket check book comprising a covering member foldable between the ends thereof, a filler end engageable with said covering member adjacent one end thereof, means adjacent one end of said filler securing said filler to said one end of said covering member, and means adjacent the other end of said covering member engageable with said one end of said filler to hold said covering member closed.

2. A pocket check book comprising a covering member foldable intermediate the ends thereof, a filler engageable with said covering member adjacent one end of said covering member, means adjacent one end of said filler securing said filler to said covering member at said one end, and hook means adjacent the other end of said covering member engageable with said one end of said filler to hold said covering member closed.

3. A check book including a covering member foldable intermediate the ends thereof, a pad of check blanks, means engaging one end of said pad with said covering member adjacent one end of said covering member, and hook means mounted on said covering member adjacent the other end thereof, said hook means adapted to engage said one end of said pad of checks en-

gaged with said covering member, to hold said covering member closed.

4. A check book including a covering member foldable intermediate the ends thereof, a pocket adjacent one end thereof, a pad of checks including an anchoring tongue adjacent one end thereof slidably engaged in said pocket to hold said pad of checks adjacent one end of said covering member, and means at the other end of said covering member, engageable over said pad of checks at said one end thereof to hold said other end of said covering member adjacent said pad of checks anchored to said covering member and thereby to hold said covering member in closed position.

5. A check book comprising a covering member, foldable intermediate the ends thereof, a filler, means adjacent one end of said filler securing said filler to said covering member near one end of said covering member, said filler comprising a book of blank checks and a book of sheets for memorandum flexibly connected together, said covering member including means adjacent the other end thereof engageable over said one end of said filler to hold said covering member closed.

6. A check book comprising a covering member foldable between the ends thereof, a filler removably secured within said covering member, a pocket adjacent one end of said covering member formed in the inner surface thereof, an anchoring tab adjacent one end of said filler engaged in said pocket, and hook means adjacent the other end of said covering member engageable with said anchoring tab secured in said pocket on said one end of said covering member to hold said covering member in folded position.

7. A check book comprising a covering member foldable between the ends thereof, a filler secured within said covering member, a hook means secured to said covering member adjacent one end thereof on one side of said fold line, and means on the inner surface of said covering member on the other side of said fold line adjacent the other end thereof securing said filler to said covering member and engageable with said hook means to hold said covering member closed.

8. A check book including a covering member, foldable between the ends thereof, hook means on one side of the fold on said covering member, hook engaging means on the other side of said fold engageable with said hook for holding said covering member closed, said hook means comprising a hook shaped flange and an anchoring plate secured thereto, said anchoring plate being enlarged at a point spaced from said hook shaped flange, and a lining member extending over the inner surface of said covering member and said anchoring plate.

9. A check book including a covering member foldable between the ends thereof, hook means for holding said covering member closed, said hook means on one side of the fold on the covering member comprising a hook shaped flange, means on the other side of said fold on said covering member engageable with said hook means, and an anchoring plate to which said flange is secured, said anchoring plate having an opening therethrough, and a lining adhered to the surface of said covering member and extending over said anchoring plate, said lining being adhered to said covering member through said opening in said anchoring plate.

10. A check book including a foldable covering member, said covering member comprising a

- covering sheet, a lining sheet adhered thereto, and a hook having an anchoring plate interposed between said lining sheet and said covering sheet near one end thereof, said lining sheet extending over said anchoring plate and adhered to said covering sheet on all sides of said anchoring plate, and means near the other end of said covering member engageable with said hook means.
- 8 11. A check book including a foldable covering member, said covering member comprising a covering sheet, a lining sheet, and a reinforcing plate embedded between said covering sheet and said lining sheet on one side of the fold, said 10 reinforcing plate including a closure hook ex-
- tending therefrom, and means on said covering member on the other side of said fold engageable with said hook.
12. A check book including a foldable covering member, said covering member including a covering sheet, a reinforcing sheet on one side of the fold, marginal edges on said covering sheet folded over said reinforcing sheet, a lining sheet extending over said reinforcing sheet overlapping said marginal edges to conceal the same, 15 and a closure hook on said reinforcing sheet, and means on the other side of the fold engageable with said closure hook.

WILLIAM ROY HOTCHKISS. 15
